[57] CLAIM

The ornamental design for a slanted holder for cutlery, as shown and described.

DESCRIPTION

FIG. 1 is a side elevational view of a slanted holder for cutlery showing my new design, the side opposite is a mirror image thereof;

FIG. 2 is a top plan view thereof;

FIG. 3 is a rear elevational view thereof; and

FIG. 4 is a front elevational view thereof.

The bottom of the slanted holder for cutlery is flat and unornamented.

The characteristic features of the design reside in the grooved edges and in the arcuately curved front and rear profiles shown in FIG. 1.
